JOHN SCOTT-TAGGART, OF ILFORD, ENGLAND, ASSIGNOR TO ALFRED ERNEST WHITE, OF LONDON, ENGLAND.

AMPLIFYING SYSTEM.

Application filed September 29, 1924. Serial No. 740,496.

To all whom it may concern:

Be it known that I, JOHN SCOTT-TAGGART, a subject of the King of Great Britain, residing at Ilford, in the county of Essex, 5 England, have invented new and useful Improvements in and Relating to Amplifying Systems (for which I have filed an application in Great Britain, No. 217,971, dated January 2, 1923), of which the following is a 10 specification.

This invention relates to amplifying systems, particularly for use in wireless telegraphy and telephony.

It is of general knowledge that when 15 there are employed two or more stages of high-frequency amplification involving the use of two or more circuits tuned to the incoming frequency, and arranged so that each of two anode circuits has a tuned circuit associated with it either by coupling or direct connection, undesirable reactions or self-oscillations will very likely occur. This 20 tendency toward undesirable reactions is due largely to capacity coupling in the 25 valves themselves.

It has been proposed to counteract the 30 tendency to self-oscillation of a single valve amplifier due to inherent capacity coupling between the electrodes of the valves by the use of a condenser connected so as to produce a reverse reaction effect, but when a plurality of stages of high-frequency amplification is involved, it has not hitherto 35 been contemplated, so far as I am aware, that similar means could be successfully applied to said systems, owing to the relatively greater difficulties involved with each successive stage of amplification. I 40 have found that by the suitable use of condensers connected to proper terminals of associated inductance coils in various stages, it is possible to neutralize this natural reaction effect and thereby insure the stability of the amplifier.

Accordingly, the invention in part consists of a high-frequency amplifier in which the currents are amplified by a plurality of stages of amplification involving a plurality of circuits, one or more condensers being connected so as to produce a reverse reaction effect to neutralize the tendency of the amplifier to generate oscillations.

A further feature of the invention consists in a wireless receiver in which the incoming high-frequency currents are ampli-

fied by a plurality of valves in cascade coupled together, by the aid of circuits substantially tuned to the incoming frequency, and in which condensers are used, in the case of at least two valves, to introduce output currents of the valves to their respective input circuits so as to neutralize the natural reaction effects in the valves concerned.

The invention also provides an amplifying system using a thermionic valve in which the natural coupling capacity between the anode and the grid electrode and their respective circuits is supplemented by a condenser, another and distinct condenser being employed to balance out the reaction effects.

Other features of the invention and the methods for carrying the same into effect will be seen from a consideration of the preferred embodiment of the same as disclosed in the accompanying drawing, and appended claims.

The diagram shows one circuit arrangement for carrying the invention into effect. This arrangement as illustrated utilizes thermionic valves designated by reference characters V_1 and V_2 which serve as high frequency amplifiers, and a third valve V_3 which acts as a detector or rectifying valve. Each of these valves, as is well known, is provided with a filament, a grid electrode and an anode.

A source of incoming signals may be a tuned antenna of the well known construction. A tuned input circuit coupled to the antenna is connected to the grid and to the filament of the valve V_1 , while the output circuit of this valve extends from its anode through the primary inductance L_3 , the high tension battery, and thence to the filament. As is well known, there exists an inherent capacity between the various elements of each valve, notably the grid electrode and anode, which in the case of the valve V_1 , is supplemented by the variable condenser C_2 . The output circuit of the valve V_1 is inductively coupled to the input circuit connected to the grid of the valve V_2 , and to the filament of this valve, and includes an inductance L_4 shunted by a variable tuning condenser.

Variable condenser C_1 is connected from the grid of the valve V_1 to one terminal of the inductance L_4 in the input circuit. The

capacity of condenser C_1 is selected with respect to the value of the inherent capacity of the valve V_1 and supplemental capacity C_2 , and is connected to the terminal of the inductance L_4 having such a polarity that the current flowing through C_1 is equal and opposite in phase to the currents flowing through the inherent capacity of the valve V_1 and its supplemental capacity C_2 .

10 The output circuit of the valve V_2 is connected from its anode through the inductance L_5 and the high tension battery to the filament of this valve, and the variable condenser C_4 is connected between the grid and

15 anode of the valve V_2 to supplement its inherent capacity. The inductance L_5 in the circuit of the valve V_2 is inductively coupled through the inductance L_6 to the input circuit of the detector valve V_3 . In this instance, also, the neutralizing condenser C_3 , which is similar to C_1 , is connected from the grid of the valve V_2 which it serves to neutralize, to one terminal of the inductance L_6 .

20 The input circuit of the detector valve V_3 is provided with a well-known grid condenser and grid leak which need not be described, while the output circuit of the detector valve V_3 includes the telephone receivers T or other indicating device in 25 series with the high tension battery. A low tension battery supplies heating current to the filaments of the respective valves through well known controlling rheostats.

25 The natural inter-electrode capacity in thermionic valves, such as that previously referred to as existing between the grid electrode and the anode, is usually of an extremely small magnitude, and consequently the balancing condenser, as for example, 30 C_1 or C_3 , must be correspondingly small. A practical difficulty is thus introduced both in the mechanical design of such a condenser and in its subsequent adjustment. For these and other reasons supplemental 35 condensers C_2 and C_4 have been introduced to increase the natural inter-electrode capacities of these valves to a magnitude which eliminates the aforesaid difficulties. There is frequently an appreciable variation in the 40 inter-electrode capacities of prevailing commercial types of thermionic valves and it has been found that the association of a supplemental capacity with the inter-electrode capacity of the valve may be used to 45 compensate for such variation and provides a convenient means for effecting a more practicable and more readily neutralized 50 inter-electrode capacity.

55 I claim:

60 1. In an amplifier, a thermionic valve having a filament, a grid electrode and an anode with inherent capacity between said last two elements, a tuned circuit connecting said grid and filament, an output circuit

extending between said anode and said filament, a transformer having a primary winding and a secondary winding, said primary winding being included in said output circuit, a rectifying device associated with said secondary winding, a condenser 70 connecting one end of said secondary winding of said transformer to said tuned circuit, and a condenser connected between said tuned circuit and said anode augmenting said inherent capacity between the grid 75 electric and anode, and said first-named condenser neutralizing the combined capacity of said inherent capacity plus the augmenting capacity.

2. An amplifying system embodying a 80 plurality of thermionic valves, each of said thermionic valves having a grid electrode and an anode between which inherent capacity exists, an input circuit connected to the grid electrode, and an output circuit 85 connected to the anode of each thermionic valve, a condenser supplementing said inherent capacity connected in parallel thereto, and a second condenser, one terminal of which is connected to the grid electrode of 90 one of said thermionic valves, the other terminal of said second condenser being connected to the input circuit of another of said thermionic valves.

3. An amplifying system embodying a 95 plurality of thermionic valves coupled in cascade, each thermionic valve being provided with a grid electrode and an anode, an arrangement for neutralizing the inherent capacity existing between the grid electrode and the anode of each thermionic valve comprising a condenser connected between the grid electrode and the anode of the thermionic valve in each stage, and a second condenser connected between the 100 grid electrodes of the thermionic valves of successive stages.

4. An amplifying system embodying a 105 plurality of thermionic valves, each of said thermionic valves being provided with electrodes including a grid and an anode coupled by an inherent electrostatic capacity, an input circuit connected to each grid, an output circuit connected to each anode, one 110 input circuit being electrically linked to an output circuit, a condenser connected between the grid and the anode of one of said thermionic valves, a second condenser connected to the grid electrode of said last 115 mentioned valve and to the input circuit of another of said thermionic valves, and means for adjusting said second condenser so that the current flowing therethrough will be equal to and opposite in phase to the currents flowing through the electrostatic capacity and through said first mentioned condenser.

JOHN SCOTT-TAGGART.
